UNITED STATES PATENT OFFICE.

ISIDOR KOKET, OF NEW YORK, N. Y.

DESIGN FOR A CROWN AND BOW FOR WATCHCASES.

58,915.

Specification for Design.

Patented Sept. 6, 1921.

Application filed August 25, 1920. Serial No. 406,027. Term of patent 3½ years.

To all whom it may concern:

Be it known that I, ISIDOR KOKET, a citizen of Poland, and a resident of the city, county, and State of New York, have invented a new, original, and ornamental Design for a Crown and Bow for Watchcases, of which the following is a specification, reference being had to the accompanying drawing, forming part thereof.

In said drawing—

Figure 1 is a front view of a crown and bow for watchcases showing my new design.

Fig. 2 is a side view thereof.

Fig. 3 is a rear view thereof.

Fig. 4 is a top plan view thereof.

The element *a* indicates a color, preferably blue, precious or semi-precious stone.

I claim:

The ornamental design for a crown and bow for watchcases as shown.

ISIDOR KOKET.
